UNITED STATES PATENT OFFICE.

ELMER A. CLARK, OF JOLIET, ILLINOIS, ASSIGNOR TO W. E. PRATT, OF CHICAGO,
ILLINOIS.

LIFTING-JACK.

1,401,761.

Specification of Letters Patent. Patented Dec. 27, 1921.

Application filed March 21, 1921. Serial No. 454,235.

To all whom it may concern:

Be it known that I, ELMER A. CLARK, a citizen of the United States, residing at Joliet, county of Will and State of Illinois, have invented certain new and useful Improvements in Lifting-Jacks, of which the following is a specification.

My invention relates more particularly to lifting jacks for carriages, wagons, automobiles and the like of the well-known type in which a lifting bar is vertically movable upon a standard by means of a rack on the bar engaged by a pair of pawls, one at least of which is carried by a pivoted lever so that by oscillating the lever in a vertical plane the lifting bar is raised step by step. Provision has been made in jacks of this character for reversing the action of the pawls so that when desired the oscillation of the lever lowers the lifting bar step by step. It is the object of my invention to provide a simple construction of jack having this reversible feature in which the reversing means is readily accessible when the jack is in operation. In one form of my invention the reversing mechanism may be operated either by the fingers or any convenient stick or tool by which the reversing mechanism may be reached without the operator being obliged to get in under the vehicle to which the jack is applied. In another form of the device the action of the pawls is reversed by means of a rod extending through or along the handle within reach of the operator without shifting from the position which he occupies when oscillating the lever handle. The preferred form of the invention is shown in the accompanying drawings and set forth in the following description. It is to be understood, however, that the specific disclosure is for the purpose of exemplification only and that the scope of the invention is defined in the following claims in which I have endeavored to distinguish it from the prior art so far as known to me without, however, relinquishing or abandoning any portion or feature thereof.

In the accompanying drawing Figure 1 is a side elevation partly in section of the preferred form of my invention, as adapted for reversing by means inside of the handle, the cover plate of the standard being removed; Fig. 2 is a vertical elevation partly

1 showing, however, the cover plate in place; Fig. 3 a horizontal section on the line 3—3 of Fig. 1 with the cover plate in place however; Fig. 4 a vertical section in a plane in the line 4—4 of Fig. 1 and Fig. 5 a side elevation partly in section of so much of that form of the invention in which the handle is provided with reversing means as is necessary to an understanding of the construction.

In the several views each part is identified by the same reference character wherever it occurs.

In the form of the invention shown in drawings, the standard 5 is preferably a casting with a suitable base 6 having a groove 7 for the reception of the lifting bar 8 and a chamber or recess 9 for the pawl mechanism. A cover plate 10 is secured to the standard after the other parts have been assembled by screws 11.

A lever 12 is pivoted on a fulcrum 13 extending between the side wall 14 of the pawl chamber and the cover plate 10 and is capable of a limited oscillation in a vertical plane. The lever comprises a socket 15 to receive a handle for oscillating the lever and a generally triangular head 16 to which pawls 17, 18 are pivoted at the upper and lower angles thereof respectively. The upper pawl is guided into the rack by the curved portion 19 of the housing and the lower pawl by the curved portion 20 of a lug 21 which may be cast integral with the standard. The pawls 17, 18 are connected together by link 22, which is pivoted at 23 to the lower pawl and has a pin and slot connection 24 with the upper pawl so as to permit a bodily movement relative to the latter. A flat spring 25 is secured at one end to a transverse member 26 on the standard and at its upper end is slidably connected to the link 22. This sliding connection is preferably formed by bending the upper end of the spring inward as at 27 and perforating the inwardly bent end to receive a vertical finger 28 which is secured to and movable with the link. At an intermediate point 29 the spring is bulged outwardly and is engaged by the reversing cam 30 which is pivotally mounted upon the lever at 31. The cam has a nose 32 which engages the bulge or curved portion of the spring and a pair of arms 33, 34 extending respectively through a slot 35 in the upper

wall of the handle socket and a slot 36 in the lower wall of the handle socket.

In the figures the parts are shown in the position which they occupy during the rising movement of the lifting bar. In this position the nose of the cam bears against the spring and the latter exerts pressure on the link 22 tending to throw the pawls 17, 18 into engagement with the rack. When 10 the handle is operated on the downward movement of the latter the lower pawl engages a tooth of the rack and raises the bar and the upper pawl slips over a tooth. When the handle is raised the upper pawl 15 maintains the rack in position and the lower pawl slips over a tooth to the one below and so on.

When the position of the cam is reversed so that it exerts no pressure on the 20 spring, the resilience of the latter acting from its point of attachment to the standard tends to force the link and consequently the pawls outward. With the parts in this position, that is to say, with the spring exerting a tension upon the pawls tending to withdraw them from the rack, when the handle is at the lower end of the stroke the lifting bar is supported on the lower pawl. As the handle rises the rack descends with 30 the lower pawl until it is engaged by the inward movement of the upper pawl due to the engagement of the latter with the curved surface 19. This releases the lower pawl which is withdrawn by the tension of the 35 spring from the rack and on the downward stroke of the handle it passes the tooth with which it has been in engagement and at the end of the downward movement of the handle it engages the tooth next above and 40 so on. Thus a very simple reversible construction is provided. The arms of the cam project beyond the upper and lower walls of the handle socket respectively and in order to shift the cam it is only necessary to 45 press against the proper arm and this may be done either by a finger or by a convenient rod or tool.

As heretofore stated it is convenient when 50 the jack is in operation and is supporting the axle of the vehicle or the like to be able to shift the mechanism to the lowering position without moving from the end of the operating handle. In the form of the device shown in Fig. 5 I have provided for this 55 method of manipulation. The lower section 37 of the handle, which may be formed with an extension if desired, is hollow, the ends thereof being blocked at 38, 39, the blocks being perforated at 40, 41 to form guides 60 for the cam operating push rod 42 which extends longitudinally of the handle. Preferably the hollow handle section is provided at its lower end with some means for interlocking it with the socket 15. For this purpose I have shown the socket as formed

with a perforation 43 and the hollow handle with a registering perforation 44 which receives a spring pressed pin 45, the spring 46 tending to force said pin outwardly. The free end of the spring is provided with a 70 thumb pin 47 by which the spring carrying the holding pin may be forced inwardly to free it from the perforation 43 in the socket. The push rod 42 is so located in the handle that when it is pushed inwardly or toward 75 the jack it engages the lower arm or horn 34 of the cam lever and shifts it from the position shown in Fig. 1 to the position for lowering the lifting bar. The push rod 42 may be shifted longitudinally in any desired manner and I have shown for this purpose a collar 48 upon the upper end of the 80 hollow section of the handle which collar is free to turn to a limited extent on the handle. The upper end of the push rod is 85 bent laterally at 49 and enters a cam slot 50 in the collar so that by turning said collar in one direction the push rod may be forced downwardly or toward the jack and by turning it in the other direction it may be 90 drawn upwardly.

The hollow handle may be of such length that the rotary collar may conveniently be located at the end thereof. If it is desired, however, an extension 51 may be provided 95 and in that case it is preferably detachably locked to the collar by spring pressed holding pin 52 operated by a thumb pin 53 which may be similar in all respects to the connection between the hollow handle section and the lever socket. Obviously if desired the handle just described may at any time be replaced by a simple bar and the reversing cam operated in the manner first described.

I claim:

1. In a lifting jack, a standard, a lifting bar vertically guided in the standard and having a rack, a lever pivoted to the standard for movement in a vertical plane, a pair of pawls engaging the rack, one at least of which is pivoted on the lever, a link connecting the pawls, a spring secured at one end to the standard and engaging the link at the other and normally exerting a pressure on the link to withdraw the pawls from the rack and means mounted on the lever for engaging the spring to reverse its action on the pawls.

2. In a lifting jack, a standard, a lifting bar vertically guided in the standard and having a rack, a lever pivoted to the standard for movement in a vertical plane, a pair of pawls engaging the rack, one at least of which is pivoted on the lever, a link connecting the pawls, a spring secured at one end to the standard and engaging the link at the other and normally exerting a pressure on the link to withdraw the pawls from the rack and a cam pivoted on the lever and

engaging the spring to reverse its action on the pawls.

3. In a lifting jack, a standard, a lifting bar vertically guided in the standard and having a rack, a lever pivoted to the standard for movement in a vertical plane, a pair of pawls engaging the rack, one at least of which is pivoted on the lever, a link connecting the pawls, a spring secured at one end to the standard and engaging the link at the other and normally exerting a pressure on the link to withdraw the pawls from the rack, a cam lever pivoted on said lever having a nose engaging the spring and an arm on the cam lever for shifting the same.

4. A lifting jack, a standard, a lifting bar vertically guided in the standard and having a rack, a lever pivoted to the standard for movement in a vertical plane, a pair of pawls engaging the rack, one at least of which is pivoted on the lever, a link connecting the pawls, a spring secured at one end to the standard and engaging the link at the other and normally exerting a pressure on the link to withdraw the pawls from the rack, a cam lever pivoted on said lever and having a nose engaging the spring and oppositely extending arms for operating the same.

5. A lifting jack, a standard, a lifting bar vertically guided in the standard and having a rack, a lever pivoted to the standard for movement in a vertical plane, a pair of pawls engaging the rack, one at least of which is pivoted on the lever, a link connecting the pawls, a spring secured at one end to the standard and engaging the link at the other and normally exerting a pressure on the link to withdraw the pawls from the rack a cam lever pivoted on said lever having a nose engaging the spring and oppositely extending operating arms, a handle socket, the latter being slotted to permit the arms of the cam lever to extend there-

45 through.

6. A lifting jack, a standard, a lifting bar vertically guided in the standard and having a rack, a lever pivoted to the standard for movement in a vertical plane, a pair of pawls engaging the rack, one at least of which is pivoted on the lever, a link con-

nnecting the pawls, a spring secured at one end to the standard and engaging the link at the other and normally exerting a pressure on the link to withdraw the pawls from the rack, a cam mounted on the lever for engaging the spring to reverse its action on the pawls, a socket on the lever into which said cam extends, a hollow handle in said socket and means movable longitudinally of the handle for actuating the cam.

7. A lifting jack, a standard, a lifting bar vertically guided in the standard and having a rack, a lever pivoted to the standard for movement in a vertical plane, a pair of pawls engaging the rack, one at least of which is pivoted on the lever, a link connecting the pawls, a spring secured at one end to the standard and engaging the link at the other and normally exerting a pressure on the link to withdraw the pawls from the rack, a cam mounted on the lever for engaging the spring to reverse its action on the pawls, a socket on the lever into which said cam extends, a hollow handle in said socket, a rod movable longitudinally of the handle and engaging the cam for shifting the same and means engaging the opposite end of the rod for shifting the latter.

8. A lifting jack, a standard, a lifting bar vertically guided in the standard and having a rack, a lever pivoted to the standard for movement in a vertical plane, a pair of pawls engaging the rack, one at least of which is pivoted on the lever, a link connecting the pawls, a spring secured at one end to the standard and engaging the link at the other and normally exerting a pressure on the link to withdraw the pawls from the rack, a cam mounted on the lever for engaging the spring to reverse its action on the pawls, a socket on the lever into which said cam extends, a hollow handle in said socket, a rod movable longitudinally of the handle, a collar rotatably mounted on the handle, a cam slot in said collar and a projection on the rod extending into said slot whereby the rotation of the collar reciprocates the rod.

ELMER A. CLARK.
